GUN

Secratus H. Cavin, 445 S. Spring St.,
Los Angeles 13, Calif.

Filed Jan. 28, 1959, Ser. No. 789,627

2 Claims. (Cl. 124—15)

This invention relates to guns and more particularly to that type of gun utilizing air pressure for a propelling force.

The invention is especially well suited for use when embodied in the form of a pistol or revolver, and is adapted to provide a strong discharging force to a small pellet as for target shooting. Then, too, the features of the guns of this invention are such that they may advantageously be embodied in a toy gun, even one which is designed to shoot Ping-pong balls, for example.

It is a general object of this invention to provide a gun of the above mentioned character which is simple and rugged in construction and reliable in operation. A gun of this invention requires but relatively light cocking force with respect to the strong propelling force which it is adapted to produce. Certain features of the gun make it safe against being fired inadvertently.

Further objects and advantages of the invention will appear during the course of the following part of this specification wherein the details of construction and mode of operation of a preferred embodiment are described with reference to the accompanying drawing, in which:

Fig. 1 is a central longitudinal vertical section through a pistol, embodying this invention, and showing the parts thereof in discharged position;

Fig. 2 is another central longitudinal vertical section through the pistol and showing the parts in cocked position; and

Fig. 3 is a cross section taken on line 3—3 of Fig. 2.

Referring to the drawing in greater detail, there is shown a gun of this invention in the form of a pistol having a body designated generally by reference numeral 10, the body of the illustrated embodiment being formed of two half portions 11 and 12 which are fastened together as with screws 13. A handle 14 is secured over the stock portion 15 of the body.

The half portions of the body have openings 18 formed therein for accommodating a cylinder 19. The cylinder has a forward wall 20 and a rearward end 21 in abutment against a wall 22 of the body openings. Cylinder 19 defines a cylindrical chamber 23 having a piston designated generally by numeral 24, the piston being reciprocable axially in the chamber. The illustrated piston comprises a rearward plate 27 having a split lug 28 extending rearwardly therefrom for pivotal connection of the piston to a piston rod 29 as with a pivot pin 30. On the forward face of the plate 27 is a leather disc 31, the margins of which are folded over the edge of a disc 32 which is secured to the plate by a screw 33. A coil spring 35 in the chamber bears at one end thereof against the rearward face of the piston plate and at its other end against the wall 22 for urging the piston forwardly in the cylinder.

A gun barrel 37 extends out from the body, it having a bore 38 extending axially therethrough from a muzzle end 39 to a breech end 40. The barrel is secured at its breech end in an opening 41 formed in the forward wall of the cylinder whereby the bore is open to the

2

cylinder chamber. The barrel has an annular enlargement 43 preferably of conical section to provide a seat into which a spherical projectile or pellet 44 becomes wedged when the piston is retracted to suck the pellet 44 against the seat.

For safety purposes, the illustrated piston is designed to be muzzle-loaded with a single pellet 44. The pellet will easily roll and drop out from the barrel unless it has become seated in the breech end of the barrel by retracting the piston.

A pin 47 extends forwardly from the piston in alignment with the barrel bore. It is long enough to extend into the barrel bore when the parts of the gun are in discharge position, as shown in Fig. 1 of the drawing. It serves to unseat the pellet 44 from seat 43 as the piston moves forwardly into the cylinder.

A rod 49 which is screw-threaded at its inner end to extend into a tapped bore formed in the forward wall of the cylinder serves along with the gun barrel to hold the cylinder secure in the gun body.

The piston is retracted by means of a hammer 51 which is pivotally mounted on a pivot pin 52 to swing rearwardly in a recess 53 formed in the gun body. The hammer comprises a thumb-grip portion 54, a head portion 55, a curved lever-arm portion 56 extending from the head portion to the lower portion of the hammer through which the pivot pin 52 extends, and a lever arm 57 extending upwardly from the pivot pin. The upper end of the lever arm 57 is forked to receive the rearward end portion 58 of the piston rod, there being a pin 59 extending through the forked end of the lever arm and through the piston rod to pivotally connect the rod to the hammer. When the hammer is released from its cocked position, it will swing forwardly until head portion 55 strikes a stop or seat 60 defining the upper forward end of the body recess 53.

The hammer is released from its cocked position by the action of a trigger 63 which extends out from a recess 64 formed in the gun body. The trigger has a lever arm 65 extending rearwardly from the upper end thereof and terminating in a finger 66. The trigger is pivotally mounted in recess 64 of the gun body by means of a pin 67 which extends through the lever arm portion 65. A trigger spring 68 is secured at one end thereof to that part of the trigger disposed forwardly of the pivot pin 67, and it extends over the rearward portion of the trigger lever arm to engage the top wall of the recess 64, thereby to bias the trigger to swing on its pivot in a trigger guard 69 in the direction of arrow 70.

The trigger is operatively associated with the piston rod and the hammer by means of catch or plate 73 which is slidably vertically in a recess 74 provided therefor in the gun body. The lower end portion of the plate 73 has an opening 75 formed therein and into which the finger 66 of the trigger extends so that when the trigger is pulled back it will slide the plate upwardly against the pressure of the trigger spring, and when the gun parts are shifted toward cocked positions, the trigger spring will cause the catch plate 73 to slide downwardly in its recess 74.

The upper end portion of the plate 73 has a longitudinally extending slot 77 formed therein, the slot terminating at its upper end in an end wall 78. There are openings 79 and 80 formed in the gun body allowing the piston rod to extend through the slot 77 to the hammer.

A notch 83 is formed in the piston rod intermediate its ends at a place where it will become engaged by the upper end wall 78 of the plate slot 77 when the hammer has been pulled back to its cocked position, thereby to hold the several gun parts in their respective cocked positions until released by a pull on the trigger.

It will be apparent that as the hammer is retracted it will pull upon the piston rod to move the piston rearwardly in the cylinder thereby to suck the projectile 44 into its seat 43. The rearward end of the piston rod will be pulled downward by the swing of lever arm 57 of the hammer, thereby allowing the catch plate to be pulled downwardly by the force of the trigger spring. When the hammer has pulled back to its cocked position, the end wall 78 in the catch plate will engage notch 83 of the piston rod thereby to hold the gun parts in cocked or ready-to-fire position.

Pulling on the trigger will cause the plate 73 to slide upwardly out of engagement with the piston rod whereby the piston spring will force the piston forwardly in the cylinder. The pin 47 on the piston will move into the breech end of the barrel to dislodge the projectile from its seat and the compressed air in the cylinder ahead of the piston will drive the projectile out through the barrel.

While the instant invention has been shown and described herein, in what is conceived to be the most practical and preferred embodiment, it is recognized that departures may be made therefrom within the scope of the invention, which is therefore not to be limited to the details disclosed herein, but is to be accorded the full scope of the claims.

What I claim is:

1. A gun comprising a body, a barrel extending out from the body and having a bore extending axially therethrough, the bore having a muzzle end and a breech end, a cylinder of greater internal diameter than said bore in the body extending rearwardly from the breech end of the bore and having a forward wall to define a cylindrical chamber in the cylinder extending rearwardly from the forward wall, said cylinder having a longitudinal axis offset from the longitudinal axis of said bore, the forward wall having an opening formed therein, the barrel being connected to the forward wall whereby the breech end of the bore is open to the chamber, the breech end of the bore having an annular taper for frictionally holding a projectile in the breech end of the bore, a piston reciprocable axially in the chamber, a spring in the chamber and engaged behind the piston for urging the piston toward the forward wall, said body including a slot portion remote from said breech end of said barrel, and adapted to receive a hammer, said hammer pivotally mounted in said slot portion rearwardly of the cylinder, a piston rod pivotally connected at one end thereof to

5

the rear of said piston and pivotally connected at its other end to the hammer whereby as the hammer is moved rearwardly in said slot portion on its pivot toward a cocked position it will retract the piston in the chamber and load the spring, the piston rod having a notch formed therein between its ends, a plate slidable transverse to the movement of said piston in the body behind the chamber and forwardly of the hammer, the plate having an elongate opening formed therein and through which the piston rod extends, the plate being slidable with respect to the piston rod from a position when the gun is cocked in which the plate engages the piston rod in the notch thereof to another position in which the plate is disengaged from the piston rod, a trigger pivotally mounted on the body and pivotally engaged with the plate for operating the plate, a trigger spring operatively associated with the body and with the trigger for swinging the trigger forwardly on its pivot to move the plate into engagement with the notch on the piston rod and a pin mounted in said piston eccentrically and protruding from the forward face of said piston and extending forwardly from the piston and in alignment with the barrel bore, the pin being of a length to extend into the bore when the piston is moved forwardly in the cylinder to unseat said projectile from the annular taper in said breech, the force of the pin against the projectile and the air pressure developed in the chamber by the forward movement of the piston forcefully ejecting the projectile out through the muzzle end of the bore.

2. A gun as defined in claim 1, wherein said hammer comprises a short lever arm extending upwardly from the pivot connection of the hammer in the body, and a curved lever arm disposed rearwardly of the short lever arm and projecting from said body through said slot portion, and said short lever arm being pivotally connected at one end of said piston rod.
